UNITED STATES PATENT OFFICE

GEORGE A. HARRIS, OF GARFIELD COUNTY, COLORADO

RIFFLE

Application filed May 19, 1928. Serial No. 279,004.

An object of this invention is to provide an improved riffle for use in the separation of value-bearing ores.

A further object of the invention is to provide an improved riffle for use in combination with an hydraulic-flow method of ore separation.

A further object of the invention is to provide an improved riffle that will thoroughly agitate the mixture passed thereover, whereby a more complete recovery of the values of the ores treated thereon will result.

A further object of the invention is to be found in the provision of an improved riffle adapted for continuous operation wherein provision is made for discharge of the ore values separate from the sludge.

A further object of the invention is to be found in the construction and arrangement of riffle bars, whereby a thorough agitation of the sludge is had and the ore values separated from and retained against the passage of the sludge.

A further object of the invention is to be found in the provision of an improved riffle that may be used as a single unit or multiplied into a series of similar units, that is simple and inexpensive of manufacture and durable and efficient in operation.

My invention consists in the construction, arrangement and combination of elements hereinafter set forth, pointed out in my claims and illustrated by the accompanying drawing, in which—

Figure 1 is a plan view of a sluice equipped with one unit of my improved riffle. Figure 2 is a side elevation of the construction shown in Figure 1. Figure 3 is a longitudinal section on the indicated line 3—3 of Figure 1.

Figure 4 is a cross section on an enlarged scale on the indicated line 4—4 of Figure 1. Figure 5 is a fragmentary detail section, on an enlarged scale showing the action of the riffle bars, the direction of flow in the sluice being as indicated by the arrows. Figure 6 is a fragmentary detail section, on an enlarged scale, illustrating a preferred method of securing the riffle bars through the use of welded fillets.

The hydraulic-flow process of ore separa-

tion is well known in its various steps and consists, generally, in running ground or pulverized ore through sluices and over riffles in company with water, the mineral values in the ore, being heavier than the dirt and rock, settle to the bottom of the sluices and are caught in amalgamating basins while the lighter material is carried away by the water. Various modifications of detail are used in carrying out the above process and various combinations of sluices and riffles may be employed, but the foregoing is sufficient for an understanding of the features embodied in my improved riffle.

In the construction of my improvement, as shown, any suitable sluice may be employed, of any desired width and depth, such a sluice being conventionally illustrated as comprising a bottom 10 and side walls 11 and 12 rising from the margins of said bottom. It is to be understood, of course, that the sluice is to be installed with its bottom 10 in an inclined position longitudinally, so that water will flow freely therethrough. The riffle comprises a plate 13, of any desired length and of a width preferably greater than that of the sluice in which it is to be mounted, the excess width of the plate 13 being bent at right angles to the plate to form a channel adapted to fit closely within the sluice and prevent escape of the minute particles of the ore values. The plate 13 may be of a width exactly equal to that of the sluice and side members may be secured thereto in place of the bent-up portions above described, the exact construction being relatively unimportant so long as a channel is provided and the material may be any suitable metal, preferably highly resistant to rust and corrosion. The upstream end of the plate 13 is secured to or overlain by the end of the preceding sluice unit and bars 14, of any desired shape in cross section, are secured to said plate throughout their lengths so that no passage is possible between the bars and plate 13, said bars extending at an angle transversely and longitudinally of said plate, in a downstream direction, and being secured at their outer ends to the channel wall, their inner ends terminating in the midstream portion of the channel in such manner that the first up-

stream bar extends most nearly across said channel and each successive bar a less distance. Any desired number of the bars 14 may be employed, four being illustrated, and the function of said bars is to agitate the mixture of water and ore and divert the flow thereof diagonally across the channel. Riffle bars 15, round in cross section and of less extent above the plate 13 than the bars 14, are secured in spaced relation to the plate 13 in a manner similar to the bars 14, said bars 15 extending at an angle transversely and longitudinally of the plate 13 in a downstream direction from the channel wall opposite to that to which the bars 14 are secured. All of the bars 15 are secured at their outer ends to the channel wall and the first few of said bars have the termination of their lengths in staggered relation with the ends of the bars 14, the remaining bars 15 extending entirely across the plate 13, through a slot in the wall 12 of the sluice and across an extension 16 of the plate 13 without the sluice. Parallel riffle bars 17 are spaced apart transversely of the plate 13 below the downstream end of the slot in the wall of the sluice and are secured to said plate throughout their lengths and to the channel walls at their ends, the plate 13 having a transverse ridge or step 18 spaced in a downstream direction from said bars 17 and the basin thus formed between said bars 17 and step 18 may contain amalgam to the end that any of the values remaining in the sludge after it has passed over the riffle bars 15 and 35 17 may be caught and retained by the amalgam in said basin.

The operation of the improvement is as follows; the mixture of water and ore enters the upstream end of the sluice containing the 40 riffle and strikes against the bars 14, thereby being thoroughly agitated and tumbled about, the current being diverted diagonally across the sluice against and across the bars 15. The bars 15, being smaller than the bars 14, do not agitate the mixture to a great degree nor do they divert the current to so great an extent as it flows across them, but being round, each bar 15 establishes and maintains an eddy current along its upstream side, as is clearly 45 shown in Figure 5, and the heavier particles of the ore, carrying the values, are caught in these eddy currents and carried slowly along one or another of the bars 15 out of the sluice and across the plate extension 16 while the 50 sludge remains in the sluice way to be directed as desired; values not caught by the bars 15 being checked by the bars 17 or caught in the amalgam in the basin between said latter bars and the step 18.

60 It is of course obvious that any number of my improved riffles may be used in a single sluice, or that the values delivered by the bars 15 and extension 16 may be directed into a series of sluices containing riffles and that 65 the riffle and its constituent parts may be of

any size to meet the needs of a given situation, the illustration and foregoing description being in no sense limitative apart from the scope of the appended claims.

I claim as my invention—

1. The combination with a sluice of a riffle comprising a relatively long channel member, riffle bars secured at one end to side walls of said channel and throughout their lengths to the bottom of said channel and extending at an angle transversely and longitudinally of said channel in a downstream direction, some of said bars extending in intersecting directions and terminating in staggered relation, and a settling basin at the 75 downstream end of said channel.

2. The combination with a sluice of a riffle comprising a relatively long channel member formed with one interrupted margin and 75

registering with the interrupted portion of said margin, spaced agitating bars secured at one end to one wall of said channel and throughout their lengths to the bottom of said channel and extending at an angle transversely and longitudinally of said channel in a downstream direction, riffle bars, round in cross section, secured at one end to the opposite wall of said channel and throughout their lengths to the bottom of said channel and extending at an angle transversely and longitudinally thereof in a downstream direction, some of said riffle bars terminating in staggered relation with said agitating bars and others of said riffle bars extending entirely across said channel, through the gap in one wall thereof and across the extension of said channel without said sluice, together with a settling basin adjacent the downstream end of said channel.

3. A riffle comprising a plate, upstanding, marginal walls longitudinally of said plate, one of said walls having a gap opening to a lateral extension of said plate, round riffle bars secured throughout their lengths to said plate and at one end each to said uninterrupted wall and extending diagonally across said plate in a downstream direction, some of said bars extending through said gap and across said extension, agitating bars on the upstream side of said gap, secured to said plate and at one end each to said interrupted wall, said agitating bars extending across said plate substantially perpendicular to said riffle bars and terminating in staggered relation with some of said riffle bars, and a settling basin between transverse spaced riffle bars and a transverse step in said plate adjacent the downstream end thereof.

4. A riffle comprising a plate, marginal walls longitudinally of said plate, one of said walls having a gap opening to a lateral extension of said plate, agitating bars on said plate adjacent the upstream end thereof and extending in a downstream direction at an an- 125
